UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

CONTROLLING DEVICE FOR FILLED-BAG-SEWING APPARATUS.

1,314,368.

Specification of Letters Patent. Patented Aug. 26, 1919.

Application filed November 30, 1917. Serial No. 204,658.

To all whom it may concern:

Be it known that I, DUDLEY S. SEYMOUR, a citizen of the United States, residing at Oak Park, in the county of Lake, State of Illinois, have invented certain new and useful Improvements in Controlling Devices for Filled-Bag-Sewing Apparatus, of which the following is a description, reference being had to the accompanying drawing and to the figures of reference marked thereon.

The invention relates to new and useful improvements in a controlling device for a filled bag sewing apparatus and more particularly to a filled bag sewing apparatus including two sewing machines each having a sewing head and a conveyer belt for presenting the filled bag to its sewing head.

In my prior Patent, No. 1,237,710, granted August 21st, 1917, I have shown a filled bag sewing apparatus including two sewing machines positioned relative to each other so that the filled bag after being stitched on one of the sewing machines may be conveyed to and stitched on the other sewing machine. In conjunction with the apparatus shown in said patent there are controlling devices whereby certain control may be had over the sewing heads and the conveyers of the respective sewing machines.

An object of the present invention is to provide improved controlling devices for a filled bag sewing apparatus of the character shown in my prior patent, which controlling devices may be operated so as to control both of the conveyer belts at either sewing station and also whereby the sewing head and conveyer belt of either sewing machine may be controlled and operated independently of the other.

In the drawings which show by way of illustration one embodiment of my invention:

Figure 1 is a front view of a filled bag sewing apparatus having my improvements applied thereto;

Fig. 2 is an enlarged view partly in front elevation and partly in section showing more or less diagrammatically the clutches and the controlling devices therefor, which operate respectively the sewing heads and the conveyer belts of the two machines; and

Fig. 3 is a view partly in plan and partly

in section showing more or less diagrammatically the filled bag sewing machines and the controlling devices therefor.

In the present embodiment of my invention, I have brought together two complete filled bag sewing machines and associated the same so that the filled bags after having been stitched on one machine may be conveyed by the conveyer belt thereof to the conveyer belt of the other machine and then stitched thereon.

It is customary in the packing of certain materials to use an inner and an outer bag. The apparatus referred to is especially designed for stitching first the inner bag on one sewing machine and then the outer bag on the other sewing machine. Each filled bag sewing machine includes clutches which may be operated so that the conveyer of the machine may be operated independently of the stitching mechanism or the stitching mechanism and conveyer may be simultaneously started and operated. My particular improvement consists in the controlling devices for these clutches. There are controlling devices for each sewing station, that is, adjacent each sewing head, so that the operator standing at the sewing head of one filled bag sewing machine may actuate the controlling devices of such machine or when standing at or adjacent the sewing head of the other machine may actuate the controlling devices therefor. These controlling devices are so constructed and connected that the conveyer belts may be simultaneously controlled from either sewing station and the conveyer belt and sewing head of either machine may be operated independently.

Referring more in detail to the drawings, my improved filled bag sewing apparatus includes a filled bag sewing machine indicated at A and a filled bag sewing machine indicated at B. These sewing machines, so far as the sewing heads and conveyer belts are concerned, are duplicates of each other and, therefore, the description of one will answer for the other, the reference letters, however, being applied to the drawings to indicate both machines.

Each filled bag sewing machine includes a frame 1 having a table 2 carrying a bracket 3. Mounted for vertical adjustment on the

bracket 3 is a sewing head 4 which is provided with a needle bar 5 carrying the needle of the stitching mechanism. This needle bar is disposed so as to operate in a 5 horizontal line. The sewing head is operated by means of a belt 7 which runs over a pulley 6 splined to a vertical shaft 8. Keyed to this shaft 8 is a clutch member 9. Associated with the clutch member 9 is a 10 clutch member 10. In line with the shaft 8 is a driving shaft 11. Keyed to the shaft 11 is a clutch member 12 which is adapted to coöperate with a clutch member 13 on a belt wheel 14, freely mounted on the shaft 11 15 and capable of endwise movement thereon. This belt wheel is preferably driven from a motor indicated at M and supported by the main frame 1. Carried by the main frame 1 and projecting laterally therefrom is a 20 supporting bracket for the conveyer belt. Mounted on this bracket are two rollers 15 and 16. The conveyer belt, indicated at 17 in the drawings, runs over these rollers. One of the rollers, preferably the roller 15 is 25 driven by a sprocket chain 18 from the sprocket wheel 19 on a cross shaft carrying a worm gear which meshes with a worm gear slidably connected to the shaft 11. The bracket for the conveyer belt is mounted on 30 two threaded shafts 20 and 21 and may be raised and lowered by the turning of these shafts. This manner of supporting the conveyer belt and driving the same so it may be adjusted vertically without disturbing its 35 driving connection with the vertical shaft 11 is substantially the same as that shown in the Foster Patent 875,339, granted Dec. 31, 1907. The belt wheel 14 as above noted is driven from a motor and this belt wheel is 40 capable of being moved endwise so as to couple the same to the clutch member 12 which will rotate the shaft 11 and thus operate the conveyer. A further endwise movement of the belt wheel raises the clutch member 45 12 which is keyed to the shaft 11 so as to bring the same into engagement with the clutch member 10 and raise said clutch member into gripping engagement with the clutch member 9 and this causes the shaft 8 50 to be driven from the belt wheel 14; and the shaft 8, as above noted, operates the sewing head. The belt wheel is shifted on the shaft 11 by a lever 22 which is pivoted at 23 to a bracket 24 attached to the underside of the 55 supporting table 2.

The controlling devices for the two filled bag sewing machines indicated at A and B are identical and each includes a knee shift lever and also a foot controlled lever. A 60 shaft 23 is mounted in suitable brackets in the frame 1 of each sewing machine. This shaft 23 has a knee shift lever 25 fixedly attached thereto. Also fixed to the shaft 23 is an arm 25. This arm 25 is connected to the lever 22 by a rod 26. The rod 26 extends

freely through an opening 27 in the arm 25 and the lower end thereof is bent as at 28. Also mounted on the shaft 23 and fixed thereto is an arm 29. The arm 29 on the sewing machine indicated at A is connected 70 to the arm 29 on the machine indicated at B, by a link 30, so that any movement imparted to the shaft 23 by the knee shift lever of one filled bag sewing machine will be likewise imparted to the shaft 23 of the 75 other filled bag sewing machine.

Also mounted on the shaft 23 so as to turn freely thereon is a foot lever 31. This foot lever has an arm 32 formed integral therewith and the shaft 23 merely serves as a 80 bearing support for this foot lever. A rod 33 is connected at its upper end to the arm 22 and at its lower end said rod extends freely through an opening 34 in the outer end of the arm 32 and said rod is bent laterally as at 35. Inasmuch as each foot lever 31 is free on the shaft 23 it will be apparent that either lever may be depressed without depressing the other foot lever and the rod 26 may slide freely through the arm 25 to 90 which it is attached so that when either foot lever is depressed the other foot lever and the clutch parts controlled thereby will not be in any way moved.

As above noted my improved filled bag 95 sewing apparatus is especially adapted for sewing an inner and also an outer bag. The filled bags are placed on the conveyer of the filled bag sewing machine A. The operator through the lever 31 may depress the lever 10 22 of said sewing machine A, sufficiently to start the conveyer of this machine only, and thus cause the filled bag to be moved along until it reaches the sewing head. By further depressing the foot lever the lever 22 10 may be depressed further at its outer end thus causing the clutch members 9 and 10 to contact and the sewing mechanism to be operated. Thus the mouth of the inner sack may be closed. The operator may 11 then, through the action of the knee shift, cause both conveyers to be operated and without operating either stitching mechanism. The filled bag will thus be carried along and delivered from one conveyer to 11 the other and brought to the second sewing head, that is, the sewing head of the filled bag sewing machine B. The operator then stepping to the other station may, by depressing the foot lever thereof, control 12 either the conveyer alone of this second filled bag sewing machine or control the conveyer and the sewing mechanism of such machine and thus close or stitch the mouth of the outer bag.

The above is only one illustration of how my improved controlling devices may be operated for controlling the conveyers and sewing mechanisms of the two machines. The essential feature consists in the capa- 130

bility of controlling the two conveyers simultaneously from either sewing station and also the controlling of the conveyers and the stitching mechanisms of either 5 filled bag sewing machine independent of the other.

It is obvious that minor changes in the 10 details of construction and the arrangement of parts may be made without departing from the spirit of the invention as set forth in the appended claims.

Having thus described my invention, what I claim as new and desire to secure by Letters Patent, is:—

15 1. The combination of filled bag closing machines each including a sewing head and a conveyer for the filled bags, said conveyers being positioned so that the filled bag is delivered from one conveyer to the other, and 20 devices for controlling the operation of both conveyers from the sewing position at either machine.

25 2. The combination of filled bag closing machines each including a sewing head and a conveyer for the filled bags, said conveyers being positioned so that the filled bag is delivered from one conveyer to the other, devices for controlling the operation of both conveyers from the sewing position at 30 either machine, and devices for controlling the operation of the sewing head and the conveyer of either filled bag machine independently of the other.

35 3. The combination of filled bag closing machines each including driving means, a sewing head, a clutch between the driving means and the sewing head, a conveyer, a clutch between the conveyer and the driving means, said conveyers being positioned 40 so that the filled bag is delivered from one conveyer to the other and devices whereby the clutches for the conveyers may be simultaneously operated from the sewing position at either machine.

45 4. The combination of filled bag closing machines each including driving means, a sewing head, a clutch between the driving means and the sewing head, a conveyer, a clutch between the conveyer and the driving means, said conveyers being positioned 50 so that the filled bag is delivered from one conveyer to the other, and devices whereby the clutches for the conveyer and the sewing head of both machines may be operated 55 from the sewing position at either machine.

55 5. The combination of filled bag closing machines each including driving means, a sewing head, a clutch between the driving means and the sewing head, a conveyer, a clutch between the conveyer and the driving means, said conveyers being positioned 60 so that the filled bag is delivered from one conveyer to the other and devices whereby the clutches for the conveyers may be simultaneously operated from the sewing position

at either machine, and devices for controlling the clutches for the sewing head and the conveyer from either sewing position independently of the other.

6. The combination of filled bag closing 70 machines each including driving means, a sewing head, a clutch between the driving means and the sewing head, a conveyer, a clutch between the conveyer and the driving means, said conveyers being positioned so 75 that the filled bag is delivered from one conveyer to the other, and devices whereby the clutches for the conveyer and the sewing head of both machines may be operated from the sewing position at either machine, and devices for controlling the clutches for the sewing head and the conveyer from either 80 sewing position independently of the other.

7. The combination of filled bag closing 85 machines each including a driving means, a sewing head, a clutch between the sewing head and the driving means, a conveyer, a clutch between the conveyer and the driving means, a lever for operating said clutches in succession whereby the conveyer may be operated independently or with the sewing head, said conveyers being positioned so 90 that the filled bag is delivered from one conveyer to the other, and devices for controlling the operation of both levers from the 95 sewing position at either machine.

8. The combination of filled bag closing 100 machines each including a driving means, a sewing head, a clutch between the sewing head and the driving means, a conveyer, a clutch between the conveyer and the driving means, a lever for operating said clutches in succession whereby the conveyer may be operated independently or with the sewing head, said conveyers being positioned so 105 that the filled bag is delivered from one conveyer to the other, devices for controlling the operation of both levers from the sewing position at either machine, and devices for controlling the operation of either lever independently of the other.

110 9. The combination of filled bag closing machines each including a driving means, a sewing head, a clutch between the sewing head and the driving means, a conveyer, a clutch between the conveyer and the driving means, a lever for operating said clutches in succession whereby the conveyer may be operated independently or with the sewing head, said conveyers being positioned so 115 that the filled bag is delivered from one conveyer to the other, a shaft supported by each machine, a knee shift for moving the shaft, an arm carried by the shaft, a rod connecting the arm to the lever for operating the 120 clutches and a link for connecting the shafts whereby the oscillation of one shaft is imparted to the other so that the conveyers may be operated from either sewing position.

125 10. The combination of filled bag closing 130

- machines each including a driving means, a sewing head, a clutch between the sewing head and the driving means, a conveyer, a clutch between the conveyer and the driving means, a lever for operating said clutches in succession whereby the conveyer may be operated independently or with the sewing head, said conveyers being positioned so that the filled bag is delivered from one conveyer to the other, a shaft supported by each machine, a knee shift for moving the shaft, an arm carried by the shaft, a rod connecting the arm to the lever for operating the clutches and a link for connecting the shafts whereby the oscillation of one shaft is imparted to the other so that the conveyer may

be operated from either sewing position, a foot lever for each machine, an arm connected to the foot lever and a rod connecting said arm with the lever of the machine 20 with which said lever is associated, the rod connection between the levers for the clutches in each machine and the arm carried by the shaft for operating the same being constructed so that said foot levers may 25 be operated independently.

In testimony whereof I affix my signature in the presence of two witnesses.
